FOREIGN PATENT DOCUMENTS

CN 3439671 * 4/2005

Primary Examiner — Catherine A Tuttle(74) *Attorney, Agent, or Firm* — Akerman LLP(57) **CLAIM**

The ornamental design for a bassinet attachment, as shown and described.

DESCRIPTION

FIG. 1 is a perspective view of the bassinet attachment embodying our design;

FIG. 2 is a first side view thereof;

FIG. 3 is a second side view thereof;

FIG. 4 is a front view thereof;

FIG. 5 is a back view thereof;

FIG. 6 is a top view thereof;

FIG. 7 is a bottom view thereof;

FIG. 8 is a perspective view showing the design in association with a bassinet in broken lines; and,

FIG. 9 is a perspective view showing the design in association with an alternate bassinet in broken lines.

The bassinets shown in broken lines are for illustrative purposes only; and form no part of the claimed design.

1 Claim, 9 Drawing Sheets(56)
